UNITED STATES PATENT OFFICE

151,295

DESIGN FOR A SOFA BED

George L. Stanley, Fort Worth, Tex.

Application April 17, 1947, Serial No. 138,462

Term of patent 14 years

(Cl. D5—4)

To all whom it may concern:

Be it known that I, George L. Stanley, a citizen of the United States, residing in Fort Worth, in the county of Tarrant and State of Texas, have invented a new, original, and ornamental Design for a Sofa Bed, of which the following is a specification, reference being had to the accompanying drawing, forming a part thereof.

I claim:

The ornamental design for a sofa bed, substantially as shown.

GEORGE L. STANLEY.
